UNITED STATES PATENT OFFICE.

LEROY S. BUFFINGTON, OF MINNEAPOLIS, MINNESOTA.

DESIGN FOR A LIGHT-FOUNT.

SPECIFICATION forming part of Design No. 30,083, dated January 31, 1899.

Application filed December 27, 1898. Serial No. 700,464. Term of patent 7 years.

To all whom it may concern:

Be it known that I, LEROY S. BUFFINGTON, a citizen of the United States, residing at Minneapolis, county of Hennepin, State of Minnesota, have invented and produced a new and original Design for a Light-Fount, of which the following is a specification, reference being had to the accompanying drawings, wherein—

10 Figure 1 is a side elevation, Fig. 2 is a central vertical section, and Fig. 3 is a front elevation, of a light-fount embodying my design.

By reference to the drawings it will be seen that the body of the light-fount is of concavo-
15 convex form and that a nipple-like projec-
tion having the appearance of a gas-burner
projects from said body of the light-fount on
the axis thereof and into its concavity. When
20 the concave surface of the light-fount is

projection appears projecting directly toward the observer and at the center of the concavity.

In a companion application for a design patent filed of even date herewith and en- 25 titled "Design for a lamp-body" I have shown and claimed a design for a lamp-body embodying as a feature the light-fount herein illus-
trated and claimed.

Having described my invention, what I 30 claim as new, and desire to secure by Letters Patent of the United States, is—

The design for a light-fount, substantially as herein shown and described.

In testimony whereof I affix my signature 35 in presence of two witnesses.

LEROY S. BUFFINGTON.
